Frederick E. Maynard.

UNITED STATES PATENT OFFICE

2,221,842

CIRCULATING AIR CONDITIONER

Charles J. Miller, Los Angeles, Calif.

Application May 8, 1939, Serial No. 272,380

2 Claims. (Cl. 126—106)

This invention is a heat generating and exchange apparatus, and more especially is an air heating and circulating furnace.

An object of the invention is to provide an extremely simple, low cost, practical, efficient, economical and compact fresh air conditioner and circulator.

A further object is to provide an apparatus of this class which is easily installed, is light in weight, is readily inspected and enables easy repair and interchange, as may be needed, of worn parts.

An additional object is to provide for a semi-automatic and positive air flow in the unit, and to so design, construct and arrange the hot gas conduits and the fresh air passageways as to most rapidly transfer the desired heat from the hot gases to the cooler fresh air.

Also an object is to provide a forced draft device in such a relation in the passageways of the unit that the heated air, or the cooled air, as the case may be, is most effectively both drawn through a system of conduits and forced to a main distributing column, an additional feature being to provide a hot gas chamber concentrically surrounding the said column.

The invention consists in certain advancements in this art as set forth in the ensuing disclosure and having, with the above, additional objects and advantages as hereinafter developed, and whose constructions, combinations, and details of means, and the manner of operation will be made manifest in the description of the herewith illustrative embodiment, it being understood that modifications, variations and adaptations may be resorted to within the scope, principle and spirit of the invention as it is more directly claimed hereinbelow.

Figure 1 is a broken-away plan of the unit, and Figure 2 is an axial, vertical section thereof.

This air conditioning furnace or unit includes a suitably insulated, preferably rectangular, exterior shell 2 of suitable height; the capacity determines the general dimensions. The shell is closed at the lower part by an elevated bottom 3 having suitable fresh air inlets 4 to supply oxygen for fuel combustion at burners 5 disposed above the bottom 3 and below a platform 6.

The upper part of the shell is closed by a drum head 7 of a hot air outlet drum chamber 20 formed above a shelf 8; the drum chamber being provided with a fume outlet 9 to a chimney or stack.

Spaced inwardly from the side walls of the shell are manifold partitions 10 which extend upward from the platform 6 to the shelf 8, and

are preferably straight from front to back of the shell.

Fresh air is served to the passages 11 and 12 between the side walls of the shell and the partitions 10 by horizontal channels 13 cross connected by a frontal channel 14. One of the channels is provided with an inlet box 15 for fresh air which enters the box either directly or by way of any suitable air-cooler 16 for conditioned air in warm or hot weather. The box 15 has a control damper 15' outwardly of its union with the cooler 16 and this latter has an inlet control damper 16'.

Spaced inwardly of the partitions 10 is a preferably cylindrical, vertical wall 17 forming therewith, between the platform 6 and the shelf 8 a combustion chamber 18 opening at 19 to the drum chamber 20, and opening at the bottom through the platform 6 and just above said burners 5.

Concentric to the chamber wall 17 is a fresh air column or tube 21 supported on and closed at the bottom by the platform 6 and passing upwardly through the shelf 8 and secured to the drum head 7 in air tight manner.

It will be seen that the heated products of combustion freely rise in the vertical combustion chamber 18 and both the inner and outer walls 10 and 17 dissipate heat to the cool air outside of the walls 10 and inside the cylindrical wall 17 which forms a heated air down draft passageway 22 to inlets 23 in the foot of the air column 21.

Means are provided to cause convection flow of cool air from the passages 11—12 over into the down draft passageway 22 and this is done by way of a series of tunnel tubes 24 connecting the partitions 10 to the inner cylinder 17 so that air may readily flow from the passage 11—12 to the passageway 22. To accelerate such convection flow the tubes 24 are inclined upwardly toward the inner passageway 22, and being directly in the path of the up-flowing hot waste fumes from the burners an efficient heat exchange is secured, in coaction with the exchange due to the hot fume engagement with the walls 10 and 17. It will thus be seen that the cool or cold air in passageways 11 and 12 receives heat from the vertical combustion chamber 18 and moves inwardly toward the center column 21 in most heated condition.

Means are provided to positively induct fresh cold air by way of the tunnel tubes 24 and then to positively force the heated air up the column 21. Such means includes a set of air propellers 55

25 and 26 fixed on a vertical shaft 27 hung by a head bearing 28 mounted in a cover 29 removably secured on the drum head 7. The lower end of the shaft 27 splines into a motor driven 5 foot bearing 30 fixed on the upper end of the shaft of a suitable motor 31. Thus by simply removing the cover 29 the shaft 27 and its propellers 25-26 can be pulled from the furnace as an organized assembly, and can be as easily 10 installed. A small housing 30' surrounds the bearing 30 to close off the burner chamber between parts 3 and 6 about the shaft 27.

A feature of the invention is the provision of suitable distributor pipes from the drum chamber 20. Each pipe includes a quarter turn bend 33 disposed directly in the hot gas drum and tapping into the sides of the upper end of the air column 21. This enables the fresh air passing out in the pipes 33 to be finally heated by the 15 hot gas in the drum before this goes out to the chimney.

The rising hot air in the column space 21a is radially diverted at the top by means of a concave inverted cone 34 forming a part of the 20 cover 29 of the space 21a.

What is claimed is:

1. For air conditioning; a furnace including an

outer casing having fresh air inlet means, a partition device spaced in from the casing to form an initial air heating space between itself and the casing and to receive air from said inlet means, a wall system spaced inwardly from the 5 partition device to form therewith a vertical draft, hot gas conduit, fuel burners at the bottom of the conduit, a drum at the top of and connected and open to the conduit for hot gas therefrom, said wall system also forming an inner heat transfer and air supply chamber, a central, vertical-axis, up-draft fresh air discharge tube surrounded by the supply chamber and extending across the drum from top to bottom and having intake communication at its 15 lower part with said supply chamber for heated air from said chamber, and fresh air distributor pipes leading from the upper extended portion of the said tube and through the drum, without communication therewith, for heating contact 20 with hot gas therein, and air flow means connecting the initial air space with the supply chamber.

2. The furnace of claim 1, the said flow means including a system of cross-tunnels through the 25 said conduit.

CHARLES J. MILLER.
